UNITED STATES PATENT OFFICE.

ALBERT PARADIS, OF PHILADELPHIA, PENNSYLVANIA.

SHIRT-SLEEVE.

945,980.

Specification of Letters Patent. Patented Jan. 11, 1910.

Application filed July 7, 1909. Serial No. 506,272.

To all whom it may concern:

Be it known that I, ALBERT PARADIS, a citizen of the United States, residing at Philadelphia, in the county of Philadelphia and 5 State of Pennsylvania, have invented certain new and useful Improvements in Shirt-Sleeves; and I do declare the following to be a full, clear, and exact description of the invention, such as will enable others skilled 10 in the art to which it appertains to make and use the same.

My invention relates to shirts and particularly to the sleeves thereof.

The object of the invention is to provide a 15 shirt having a short sleeve and a detachable long-sleeve upon which the cuff is supported.

A further object of the invention is to support a sleeve of this type adjustably upon the shirt whereby the shirts having a certain 20 collar-band may be adapted for persons having different lengths of arms.

A still further object of the invention is the provision of a shirt of this character in which the outer sleeve may be removed with 25 the cuff upon it, so that the user may work in the short sleeve, which is permanently secured to the shirt, during the day and place the long sleeve upon the shirt after work, so that the cuffs will present a neat appearance 30 projecting below the coat and the long sleeves will surround the entire length of the short sleeves and thereby protect the upper arm and shoulders of the wearer.

With these and other objects in view, the 35 invention consists of certain novel features of construction, combination and arrangements of parts as will be more fully described and particularly pointed out in the appended claim.

40 In the drawings, Figure 1 is an elevation of the shirt showing one of the sleeves secured to the shirt and exposing the short sleeve at the opposite side of the shirt; and

Fig. 2 is a detail perspective view of one of 45 the sleeves removed from the shirt.

Referring more especially to the drawing, 1 is the body of the shirt which, in this instance, has attached to it, a pair of short sleeves 2. The upper portion or yoke 3, of 50 the shirt is provided with a plurality of button-holes 4, which are adapted to receive the connecting stud 5. The attachment consists of a pair of sleeves 6, having cuffs 7, mounted thereon and each sleeve provided with an arm-hole 8, of sufficient size to make the 55 sleeve adjustable as will hereinafter be described. The upper portion of the sleeve is provided with a projecting tab or extension 9, in which is formed a button-hole 10, adapted to receive the stud 5. The stud may 60 be placed in any of the button-holes 4, and thus a wide range of adjustment is assured.

In use, the sleeve 6, is worn with the shirt when desired and removed by simply disengaging the tab 9, from the stud 5. 65

It will readily be seen that when the tab 9 is connected with the stud the long sleeves are secured to the shirt so that they completely cover and surround the short sleeves, whereby the shoulder and upper arm of the 70 wearer are perfectly protected.

From the foregoing description, taken in connection with the accompanying drawing, the construction and operation of the invention will be readily understood without requiring a more extended explanation. 75

Various changes in the form, proportion and the minor details of construction may be resorted to without departing from the principle or sacrificing any of the advantages of 80 this invention.

Having thus described my invention, what I claim is—

A shirt comprising a body having a plurality of button-holes formed in the yoke 85 thereof, a stud adapted to enter one of said holes, short sleeves sewed on said shirt, long sleeves having enlarged arm-holes, and an extension tab secured to the upper portion 90 of the long sleeves and provided with a button-hole to receive said stud whereby the long sleeves may be adjustably secured to the shirt over and surrounding the entire length of the short sleeves.

In testimony whereof I have hereunto set 95 my hand in presence of two subscribing witnesses.

ALBERT PARADIS.
